UNITED STATES PATENT OFFICE.

WILLIAM G. PROBST, OF LOUISVILLE, KENTUCKY.

DESIGN FOR A KITCHEN SINK.

No. 38,265.

Specification for Design.

Patented Oct. 2, 1906.

Application filed August 17, 1906. Serial No. 331,094. Term of patent 14 years.

To all whom it may concern:

Be it known that I, WILLIAM G. PROBST, a citizen of the United States, residing at Louisville, in the county of Jefferson and State of Kentucky, have invented a certain new, original, and ornamental Design for Kitchen-Sinks, of which the following is a specification, reference being had to the accompanying drawing, forming part thereof.

The figure of the drawing is a perspective view showing the design.

I claim—

The ornamental design for a kitchen-sink, as shown.

WILLIAM G. PROBST.
